UNITED STATES PATENT OFFICE.

CHARLES LEROY PARKER, OF BARBERTON, OHIO, ASSIGNOR TO THE DUNHAM COMPANY, OF BEREAL, OHIO, A CORPORATION OF OHIO.

HEATER.

Application filed November 6, 1922. Serial No. 599,474.

My invention relates to improvements in heaters, and more particularly to that type or class commonly known as "water heaters".

The primary object of the invention is to provide a generally improved heater of the class indicated which will be exceedingly simple in construction, cheap of manufacture, and efficient in use.

A further and very important object is the provision of an improved heater flue or coil for such heaters through the provision of a novel construction and arrangement of heater coils and baffle forming loops communicating with the combustion and liquid circulating chambers, respectively. More specifically stated, my improved heater flue embodies a plurality of superposed link-shaped coils providing convolute gas passages and intermediate transversely elongated or flattened hollow loops forming baffles for diverting the products of combustion into and through said gas passages of said link-shaped coils, said baffle forming loops communicating with the water or liquid chamber of the surrounding heater body.

A further and very important object is the provision of an improved heater body and coil having its parts and features of construction so disposed and arranged relative to each other that the same may be cast of suitable metal as a one-piece article of manufacture, thereby resulting in greater economy in manufacture, use and efficiency.

A still further object is the provision of a one-piece or cast heater provided with a liquid circulating chamber and an integral heating flue and having an improved form and arrangement of clean-out door at one side affording access to the water chamber and exterior portions of the heating flue or coil.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1 is a side elevation of a heater constructed in accordance with this invention, the clean-out door being removed to illustrate the interior part.

Fig. 2, a central vertical sectional view of the same.

Fig. 3, a top plan or end view of the same.

Fig. 4, a transverse horizontal sectional view, taken on line 4—4 of Fig. 1.

Fig. 5, a fragmentary cross sectional view showing a modified form of the enlarged central connecting portion midway between the ends of the heating flue or coil.

Fig. 6, a central vertical sectional view of the improved heater.

Similar numerals of reference designate like parts throughout all the figures of the drawings.

The improved heater body 1, may be of any suitable and convenient form that adapts itself to be readily cast as a one-piece body and with a clean-out opening at one side if desired. In the present instance, the heater body 1 is of square or rectangular shape forming a liquid or water circulating chamber 1^a, and a subjacent combustion or burner chamber 2. In the present instance, the heater body 1 is provided at one side with a clean-out door opening 3, of relatively large dimensions, as shown, and surrounded by border flange 4, to make a tight or liquid sealed joint with the door or cover 5. In the present instance, the border flange 4 is provided with a series of bolt receiving openings 4^a, adapted to receive and carry a series of securing bolts 5^a, and securing the cover 5 in position.

The heater flue 6, in the present instance is cast integral with the heater body 1 and extends through the water circulating chamber 1^a, terminating, in the present instance, at the top in a flange 7, for receiving a suitable chimney pipe for conducting the products of combustion to a chimney or other suitable outlet. In the present instance, the top of the heater body is provided with threaded openings 8, one of which may be closed by a suitable plug and the other connected to a suitable water pipe, a third threaded opening 9 being provided for a second conductor pipe communicating with the water circulating chamber. In the present instance, the heater flue 6 is provided with an enlarged central portion 10,

and a series of vertically arranged superposed double coils 11, as indicated.

As a means of providing circuitous or tortuous heat and water circulating passages for the products of combustion entering the flue from the combustion chamber 2 and the water enclosed within the circulating chamber.

ber 1^a, I construct the flue 6 to provide a vertically superimposed succession of link-shaped coils 11 providing convolute gas passages, the outer walls of which are provided by the undulating outer wall of the flue, the inner walls of the passage being provided by the walls of a plurality of open-ended flattened loops 11^a providing cross water passages 12, which, respectively, 13 occupy the center portion of the superimposed convolute coils, and, in addition to their water circulation function, constitute baffles overlying the reduced neck portions 15 of the structure which constitute the communicating center passages between the respective link-shaped convolute passages. These water passages, being open at their ends, afford a plurality of cross connections 20 leading through the flue to the water spaces on opposite sides of the flue and serve to direct currents of water back and forth directly through the flue structure at different levels throughout the height thereof.

This arrangement insures that the products of combustion will be repeatedly divided and alternately united throughout their passage through the flue and further provides that the products of combustion upwardly flowing in a united current through 25 the centrally disposed reduced neck portions of the flue will strike bodily against the baffling walls of the cross water passages, so that the water at several different levels will be brought into direct contact with the 30 united centrally upflowing gas stream in a manner to effectively insure the radiation of heat units and prevent an excessive escape of such units from the top of the flue.

The arrangement is one which provides 40 not only for the sinuous flow of the gaseous products of combustion but also provides for a back and forth circulation of the water through the independent open-ended cross water passages at several levels which 45 tends to permit circulation and enlarge the radiating area of the flue to a highly desirable extent.

Having thus described one of the embodiments of my invention, without having attempted to set forth all the forms in which 50 it may be made, or all the modes of its use, what I claim and desire to secure by Letters Patent is,—

1. In a water heater, the combination of 55 an outer shell and an inner flue portion furnishing a water chamber between the two, a combustion chamber below the flue and freely communicating therewith, the flue being configured to afford superposed pairs of outwardly protruding convolute gas passages separated from one another by open ended cross water passages opening into the water chamber, adjoining pairs of convolute gas passages being connected by 60 an intermediate neck portion for the pas-

sage of gases upwardly beneath the walls of the superposed cross water passage, the latter forming a baffle for diverting the upwardly flowing gases laterally into the convolute gas passages, and the flue terminating in a discharge passage leading through the water chamber and out of the shell, substantially as described. 79

2. In a water heater, the combination of 75 an outer shell and an inner integrally formed flue portion furnishing a water chamber between the two, a combustion chamber below the flue and integrally formed therewith and freely communicating therewith, the flue being configured to afford superposed pairs of outwardly protruding convolute gas passages separated from one another by open ended cross water 80 passages opening directly into the water chamber, the pairs of convolute gas passages being connected by intermediate neck portions for the passage of gases upwardly beneath the walls of the cross water passages, the latter forming baffles for diverting the upwardly flowing gases laterally into the convolute gas passages, and the flue terminating in a discharge passage leading through the water chamber and out of the shell, substantially as described. 85

3. In a water heater, the combination of 90 an outer shell and an inner flue portion furnishing a water chamber between the two, a combustion chamber below the flue and freely communicating therewith, the flue being configured to afford superposed pairs 100 of outwardly protruding convolute gas passages separated from one another by open ended cross water passages opening into the water chamber, the pairs of convolute gas passages being connected by intermediate 105 neck portions for the passage of gases upwardly beneath the walls of the cross water passages, the latter forming baffles for diverting the upwardly flowing gases laterally into the convolute gas passages, and the upper pair of convolute gas passages uniting in a discharge passage leading upwardly through the water chamber and out of the shell, substantially as described. 110

4. In a water heater, the combination of 115 an outer shell and an inner integrally formed flue portion furnishing a water chamber between the two, a combustion chamber below the flue and integrally formed therewith and freely communicating 120 therewith, the flue being configured to afford superposed pairs of outwardly protruding convolute gas passages separated from one another by open ended cross water 125 passages opening directly into the water chamber, the pairs of convolute gas passages being connected by intermediate neck portions for the passage of gases upwardly beneath the walls of the cross water passages, the latter forming baffles for divert- 130

ing the upwardly flowing gases laterally into the convolute gas passages, and the upper pair of convolute gas passages uniting in a discharge passage leading upwardly through the water chamber and out of the shell, substantially as described.

5. In a water heater, the combination of an outer shell and an inner integrally formed flue portion furnishing a water chamber between the two, a combustion chamber below the flue and integrally formed therewith and freely communicating therewith, the flue being configured to afford superposed pairs of outwardly protruding convolute gas passages separated from one another by open ended cross water passages opening directly into the water

chamber, the bottom walls of said cross water passages converging downwardly toward the center, the pairs of convolute gas passages being connected by intermediate unobstructed neck portions for the passage of gases upwardly beneath the downwardly converging walls of the cross water passages, the latter forming baffles for diverting the upwardly flowing gases laterally into the convolute gas passages, and the upper pair of convolute gas passages uniting in a discharge passage leading upwardly through the water chamber and out of the shell, substantially as described.

In testimony whereof I affix my signature.

CHARLES LEROY PARKER.
